COMBINED CAMERA AND FLASH ATTACHMENT

Alfred Winkler, Munich, and Norbert Schlagheck and
Herbert Schultes, Furstenfeldbruck, Germany, assignors
to Agfa-Gevaert AG, Leverkusen, Germany

Filed Feb. 19, 1974, Ser. No. 443,924

Claims priority, application Germany Aug. 17, 1973

Term of patent 14 years

Int. Cl. D16—01

U.S. Cl. D61—1 B

FIG. 1

FIG. 2

FIG. 1 is a front perspective view of a combined camera and flash attachment in a closed condition showing our new design;

FIG. 2 is a rear perspective view thereof;

FIG. 3 is a front perspective view thereof showing the design in open condition; and

FIG. 4 is a right end elevational view thereof.

We claim:

The ornamental design for a combined camera and flash attachment, substantially as shown.
